DESIGN FOR A NOZZLE ATTACHMENT FOR AIR HOSE OR THE LIKE

Lowell L. Smith, Webster City, Iowa

Application June 14, 1945, Serial No. 120,081

Term of patent 14 years

(Cl. D62—2)

To all whom it may concern:

Be it known that I, Lowell L. Smith, a citizen of the United States and a resident of Webster City, in the county of Hamilton and State of Iowa, have invented a new, original, and ornamental Design for a Nozzle Attachment for an Air Hose or the Like, of which the following is a specification, reference being had to the accompanying drawing, forming part thereof, in which:

Fig. 1 is a top view of a nozzle attachment for an air hose or the like showing my new design;

Fig. 2 is a side view of the same;
Fig. 3 is a front view of my new design; and
Fig. 4 is a rear view of my new design.

I claim:

The ornamental design for a nozzle attachment for an air hose or the like, substantially as shown.

LOWELL L. SMITH.
